CLAIM

The ornamental design for a chaise lounge, as shown and described.

DESCRIPTION

FIG. 1 is a front perspective view of a chaise lounge.

FIG. 2 is a front elevation view of a chaise lounge.

FIG. 3 is a rear elevation view of a chaise lounge.

FIG. 4 is a right side view of a chaise lounge.

FIG. 5 is a left side view of a chaise lounge.

FIG. 6 is a top view of a chaise lounge.

FIG. 7 is a bottom view of a chaise lounge; and,

FIG. 8 is a rear perspective view of a chaise lounge.

The broken lines in the drawings depict portions of the chaise lounge that form no part of the claimed design.
